UNITED STATES PATENT OFFICE.

DWIGHT F. BOYDEN, OF BOSTON, MASSACHUSETTS.

SHAFT FOR GOLF CLUBS OR THE LIKE.

Application filed March 5, 1927. Serial No. 173,005.

This invention relates to shafts more particularly intended for use in golf clubs, and has for its object to provide a shaft which is constructed to withstand effectively the stresses of use, which will possess the proper "life and feel", and with which high driving power may be realized.

Heretofore, hickory has been considered the most suitable material for golf shaft construction, but good grade hickory is difficult to procure. Shafts made entirely of bamboo have been tried, and while excellent in certain respects, do not endure long under the stresses of play. If it is attempted to combine hickory and bamboo as by gluing strips of bamboo into recesses formed in a hickory core, it is found that the bamboo strips loosen under the stresses of play, and the shaft loses in driving power.

It is well known that different parts of the shaft have to withstand different strains, and that a shaft usually breaks a short distance above the head, for it is here that the torsional stress caused by hitting the ball off center of the shaft is greatest, and gradually decreases toward the grip end of the shaft. It is also well known that the driving power of the shaft occurs at its grip end, and that bamboo is a resilient material which transmits this driving power effectively to the head end, but which is not very effective to take torsional stress.

With the foregoing facts in mind, the shaft of the present invention comprises a lower section made entirely of a wood such as hickory up to and above the point where maximum strain occurs, and above this point there is formed a central, longitudinal, tapering slot to receive a correspondingly-shaped lower end of an upper section of a material such as bamboo, this latter section being extended to a point sufficiently above the lower section to provide a handle portion. With such a shaft, great driving power may be realized, and the proper resistance to the stresses of use afforded.

Further features, advantageous details and combination of parts will appear from the following more complete description of an embodiment shown on the accompanying drawings, wherein

Figure 1 represents in perspective a plurality of strips of bamboo to be assembled

for the construction of the upper section.

Figure 2 is a side view of the assembled strips, the dotted outline showing the strips before they are cut to fit into the lower section.

Figure 3 is a plan view of the same.

Figures 4 and 5 represent sections on the lines 4-4 and 5-5, respectively, of Figure 2.

Figure 6 is a plan view of the lower end of the assembled upper section.

Figure 7 illustrates in front view the shaft assembled with a head.

Figures 8, 9, 10 and 11 represent sections on the lines 8-8, 9-9, 10-10 and 11-11, respectively, of Figure 7.

Figure 12 illustrates in perspective a finished golf club.

Referring to Figure 7 of the drawings, 1 represents the lower shaft section, which may be made of hickory or its equivalent. A longitudinal, tapering slot 2 extends centrally downwardly to a point somewhat above that at which maximum stress usually occurs, thus leaving a pair of fork members *f* of gradually diminishing thickness toward their ends, projecting from the uncut portion *p*. The slot 2 serves for the reception of a mating longitudinally wedge-shaped upper section 3, which may be made of bamboo or other material of like characteristics.

As shown in Figure 1, the section 3 is made up of a plurality of bamboo strips 4, 5, and 6, of different lengths, nested together. Inasmuch as the strongest and most resilient part of bamboo is its outer or enamel portion *o*, the upper section is preferably made in such a way as to retain a maximum of this part of the bamboo. To this end, the inner or pith side *i* of each of the strips is cut to fit onto the enamel portion of the immediately adjacent strip, the enamel portion of which latter has been smoothed down sufficiently to make a nice fit. The section 3 thus comprises the strip 6 extending throughout the entire length of the section, reinforced by the shorter strips 5 and 4 on its concave side. The strips are assembled and glued or cemented together as shown in dotted outline in Figure 2, whereupon the assembly is cut, as shown in full lines, to fit in the slot 2. Thus, the

convex side of the assembled strips is skived off along the plane $a-a$, and the concave side along the plane $b-b$, to provide flat surfaces for gluing onto the inner faces of the fork member j . The planes of skiving terminate sufficiently short of the upper end of the strips to provide a handle portion h made entirely of bamboo. The section 3 is inserted in the slot 2 and glued or cemented in place, and the rough shaft is then turned down to size as on a lathe, it preferably being made to taper as usual from the grip to the drive end, as shown. By constructing a shaft as hereinbefore described, a minimum of the enamel portion of the bamboo is sacrificed. Furthermore, the bamboo strips are nested to one another substantially in their natural curvature, and, due to the non-homogeneous nature of this material, the center of torsional stress or neutral axis is eccentric to the axis of the shaft, which appears to give desirable characteristics to the shaft.

As indicated in Figure 7, a head 10 when assembled with the shaft is preferably mounted thereon, with its striking face 11 on the same side as the enamel side of the wedge, as such a stick is very effective against the stresses of use. The shaft may be wrapped with cord or other suitable reinforcing material r , at the lower end of the slot 2 and a short distance below the grip end.

While I have described an upper section as comprising three strips of bamboo, a greater or less number of strips may be used, when desired. Also, if desired, this section may be one-piece when made of a suitable material; or it may be made up of a plurality of strips of the same or dissimilar woods, or of wood and bamboo. Shafts possessing different characteristics may thus be constructed, and demands of different players met. While in the particular shaft described hickory and bamboo were used, other woods may be employed in lieu thereof. For instance, ash, lancewood, or green-heart may be used in lieu of hickory, and black palm, Bethabara, and other woods and canes may be used alone or in combination, in lieu of bamboo.

Having thus described an embodiment of this invention, it is obvious that it is susceptible of change and modification without departing from the spirit or scope of invention as defined by the appended claims.

What I claim is:

1. A shaft of the class described, comprising an upper section made of a plurality of strips of bamboo of different lengths nested together, and a lower section into which said upper section is fitted.

2. A shaft of the class described, comprising an upper section comprising a plurality

of strips of bamboo nested together, the pith side of each strip being cut to receive the enamel side of the strip adjacent thereto; and a lower section fixed to said upper section.

3. A shaft of the class described, comprising overlapping upper and lower sections, said upper section comprising a plurality of strips of bamboo nested together and extended to a point sufficiently above the lower section to provide a handle portion.

4. A shaft of the class described, comprising a lower section provided with a tapering slot terminating at a point above its lower end, and an upper, wedge-shaped section fitted into the slot of said lower section.

5. A shaft of the class described, comprising a lower section provided with a central, longitudinal, tapering slot terminating at a point above its lower end to form a pair of longitudinally extending fork members, and an upper, wedge-shaped section fitted into the slot of said lower section and secured to said fork members, said upper section extending sufficiently above the upper end of said lower section to provide a handle.

6. A shaft of the class described, comprising a lower section provided with a tapering slot terminating at a point above its lower end and an upper, wedge-shaped section made up of a plurality of strips of bamboo fitted into said lower section.

7. A shaft of the class described, comprising a lower section provided with a tapering slot terminating at a point above its lower end, and an upper, wedge-shaped section comprising a plurality of strips of bamboo of different lengths nested together, fitted into said lower section.

8. A shaft of the class described, comprising a lower section provided with a tapering slot terminating at a point above its lower end, and an upper, wedge-shaped section comprising a plurality of strips of bamboo of different lengths nested together, fitted into said lower section and extending sufficiently beyond the upper end of said lower section to form a handle.

9. A shaft of the class described, comprising a lower section provided with a tapering slot terminating at a point above its lower end, and an upper, wedge-shaped section comprising a plurality of strips of bamboo fitted into said lower section, the pith side of each strip being cut to receive the enamel side of the strip adjacent thereto.

10. In combination with a shaft of the class described, comprising a lower section provided with a tapering slot terminating at a point above its lower end, and an upper section fitted into said lower section and made up of a plurality of strips of bamboo, the pith side of each of which nests onto the enamel side of the strip adjacent thereto.

to, of a head mounted on said shaft with its striking face on the same side as the enamel sides of said strips.

11. A shaft of the class described, comprising a longitudinally wedge-shaped upper section extending the full diameter of the shaft and made of a plurality of strips

of bamboo and having flat side faces, and a lower section comprising members overlapping and fixed to said faces. 10

In testimony whereof I have affixed my signature.

DWIGHT F. BOYDEN.
